UNITED STATES PATENT OFFICE.

ENOCH RECTOR, OF NEW YORK, N. Y.

FLUID-OPERATED ENGINE.

1,310,712.

Specification of Letters Patent. Patented July 22, 1919.

Application filed April 26, 1913, Serial No. 763,726. Renewed December 12, 1918. Serial No. 266,513.

To all whom it may concern:

Be it known that I, ENOCH RECTOR, a citizen of the United States, residing in the borough of Manhattan of the city of New York and State of New York, have invented 5 certain new and useful Improvements in Fluid-Operated Engines, of which the following is a specification.

My invention relates to engines actuated 10 by liquid under pressure of an expanding steam or other fluid.

One of the objects of my invention is to provide a fluid operated engine in which steam of any desired degree of super-heat 15 and any desired pressure may be used with a liquid hydro-carbon, without destroying or disintegrating the liquid.

Another object of the invention is to provide means whereby the pressure of the 20 steam may be distributed evenly over the surface of the liquid so as to provide a practically solid liquid stream or piston.

Another object of the invention is to provide means for positively actuating the steam 25 or other fluid inlets and outlets comprising a plate or a similar device normally in contact with the surface of the liquid.

Still another object of the invention is to provide means whereby the nozzles or similar device for directing the streams of liquid 30 against the motor may be controlled from a single operating lever.

Still another object of my invention consists in providing a plurality of motors rigidly secured with relation to each other and 35 which are connected to driving shafts in such a manner as to compensate for variations in the movement of said driving shafts.

The various other objects of the invention 40 will be more fully set forth in the following description of one form of engine embodying my invention, which consists in the several features of construction and combinations of parts hereinafter pointed out and 45 claimed.

In the accompanying drawings:

Figure 1 is a plan view of a preferred embodiment of my invention with certain parts broken away for clearness;

Fig. 2 is a side elevation partly in section;

Fig. 3 is a sectional view on the line 3—3 of Fig. 1 looking in the direction of the arrows and showing a connection with an 55 automobile driving shaft;

Fig. 4 is an enlarged elevation of the steam inlet valve control mechanism;

Fig. 5 is an enlarged sectional view on the line 4—4 of Fig. 4 looking in the direction indicated by the arrows and showing certain parts in elevation and other parts broken away;

Fig. 6 is a plan view of the nozzle control with a portion of one side broken away to show the different size transverse nozzle 60 passageways;

Fig. 7 is an enlarged sectional view taken on the line 7—7 of Fig. 6 and looking in the direction indicated by the arrows;

Fig. 8 is a similar view taken on the line 70 8—8 of Fig. 6 looking in the direction indicated by the arrows;

Fig. 9 is a plan view of the cylinder and opening for the communicating pipes;

Fig. 10 is a sectional view through the 75 cylinder casing taken on the line 10—10 of Fig. 9 looking in the direction indicated by the arrows;

Fig. 11 is a sectional view taken through the conduits leading from the cylinder and 80 taken on the line 11—11 of Fig. 9 looking in the direction indicated by the arrows, and

Fig. 12 is a sectional view of a part of the exhaust pipe showing a check valve therein.

Broadly considered, the engine comprises 85

an impulse wheel or an impulse and re-action wheel or a combination of such wheels, such as a pair of Pelton wheels constituting the motor, one of said wheels being adapted to drive in a forward direction and the other 90 in a reverse direction and having oppositely disposed buckets for this purpose. Streams of liquid are forced under pressure against said wheels from one or a plurality of reservoirs provided with suitable outlets and inlets for admitting elastic fluid under pressure which are controlled in such a manner as to realize a high ratio of expansion of the elastic fluid without impairing the efficiency 95 of the liquid. The reservoir communicates with a plurality of pipes or ducts, each provided with a nozzle adjacent one of said 100 wheels to direct the stream of liquid against the same. The supply of liquid through the nozzles is controlled by suitable means to direct the streams of liquid either against the forward driving or the reverse driving motor as desired or both nozzles applicable to one wheel will rotate that wheel in the same direction and reversely as to the other wheel 105

110

when supplied by one or both of its nozzles.

Referring to the particular form of engine illustrated in the drawings, there is shown a suitable casing 1 adapted to house the motor and actuating mechanism which are directly supported from a horizontally disposed bed plate 2 provided with openings to permit the motor driving liquid to flow into the lower portion of the casing containing the reservoirs for the liquid. The motor wheels 3 are provided with hollow hubs 4 which are fastened together at their inner ends to form a housing for the driven shaft 5 and its gearing connection with the motor. The hubs are mounted on spaced standards 6-6 fixed to the plate 2 and supported in suitable anti-friction bearings 8 carried by said standards.

The driven shaft 5 is split intermediate its length, extends through sleeves 7-7 in the hubs 4 and has its outer ends journaled in anti-friction bearings 9 supported by the standards 6-6 and spaced from and independent of the bearings 8 but co-acting therewith to form a lubrication containing chambers 10. The motor is connected to the shafts 5 in any suitable manner preferably by a differential gearing comprising beveled gears 11 fixed on adjacent ends of the shaft sections and meshing with the beveled pinions 12 rotatably mounted upon opposite ends of a pin 13 suitably affixed to the hubs 4.

Motion from the shaft 5 may be utilized for any useful purpose and there is shown in Fig. 3 an arrangement to drive axles 14 through the pinions 15 and gear wheels 16.

The liquid driving mechanism comprises cylinders 17 each having its lower head positioned adjacent the bottom of the casing 1 and having an inlet 18 normally closed by an inwardly-opening spring-pressed valve 19 guided by a spider 20 affixed to the underside of the cylinder. Each cylinder 17 has a liquid outlet passage 21 leading to a pair of conduits having a one-way valve 22 which acts to maintain the conduits filled at all times with a portion of the liquid to form a solid liquid piston.

50 Reciprocating in each cylinder 17 is a baffle plate 23 constituting a means for maintaining the expansive driving fluid such as steam separate from the liquid. The baffle plates have a snug fit with the side walls of the cylinders and preferably have their edges formed with flanges 24 having grooves 25 therein adapted to contain some of the liquid in the cylinder to form a liquid packing between the plates 23 and the inside walls of the cylinders.

A stem 26 extends from each baffle plate through a suitable packing in the upper head of the cylinder and has attached thereto a link 27 pivoted to one end of a lever 28 65 the other end of which lever is engaged by a

spring 29 for automatically returning the plate 23 to the raised position and closes the exhaust as shown in Fig. 2.

Steam or other actuating fluid under pressure is admitted to the portion of each cylinder 17 above its plate 23 and on the side thereof opposite the liquid inlet and outlet, from a steam supply pipe 30 which leads into a valve chest 31 containing a valve 33 of any suitable construction controlling the steam inlet port 32.

Each inlet valve is controlled from a trip mechanism which produces an extremely rapid opening of the valve. Said mechanism comprises a valve link 34 which has its lower end connected with the steam inlet valve and is actuated from the sliding frame 35 through cranks 36 and link 37. The frame 35 is slidably mounted upon one of a pair of posts 38 the upper ends of which are connected by a head plate 39. Forming part of the frame 35 and projecting toward the link 37 is a pair of vertically spaced sleeves 40 and 41 extending through which is a rod 42 provided with a pin 43 movable in the space between the sleeves 40 and 41. The lower end of the rod 42 has a spring seating head 44 bearing upon which and upon the sleeve 41 and guided on the rod 42 is a compression spring 45. The upper end 95 of the rod 42 above the sleeve 40 is formed into a beveled head or wedge 46 and the rod is held against rotation by any suitable means such as a pin 47 extending through a slot in the sleeve 41. Disposed in the path 100 of the upward movement of the beveled head 46 is a roller 48 mounted on a stud shaft 49 projecting from the long upper arm of a bell-crank lever 50 which is pivoted to the frame 35 by means of a pin 51 positioned out of 105 line with the rod 42.

The roller 48 is firmly held in its position against a stop 52 supported on the plate 39 by means of the tension spring 35^a, which is secured at its lower end to the frame 35 and at its upper end to the head plate 39. The return spring 55 may also assist in holding the roller 48 in position relative to the stop 52. The roller is so positioned that when the beveled head 46 is raised to engage therewith, both the roller and the arm 50 are forced outwardly until they reach an incline 53 on the stop 52 and are then snapped upwardly by the pressure of the springs 45 and 35^a, thus instantaneously opening the 110 steam inlet valve. A cushion spring 59 may be provided to prevent shock or jar on the quick upward movement of the frame. Mounted on the lower arm of the lever 50 is a roller 54 which, while the inlet valve is being opened is rocked into the path of a lateral projection or disk 57 having a beveled contact surface 58 that is secured to the rod 26. 115

Each cylinder 17 has a steam exhaust port 60 controlled by a valve 61 engaged by a 130

spring 62. Extending from each valve is a stem 63 provided with operating collars 64 in the path of a lug or arm 28^a of the lever 28. Said collars are suitably spaced apart 5 so that one will be engaged by the projection to positively close the valve and the other will be engaged to positively open the valve at the desired instant of time. The spring 62 is of sufficient strength to hold the valve 10 61 open against any pressure of escaping steam after it has once been opened by the lug 28^a. A check valve 64^a indicated at Fig. 12 is preferably provided in the exhaust pipe 64^b to retard the steam outlet sufficiently to 15 prevent violent return movement of the baffle plate.

The liquid forced from each cylinder 17 passes through a pair of conduits 65 extending through the bed-plate. One of the conduits 65 terminates in a post 66 and the other conduit 65 leads to a horizontally disposed connection which constitutes a side extension from a sleeve 67. This sleeve is provided with two pairs of oppositely disposed 20 openings, one pair formed of an aperture 68 disposed vertically above the bore of the post 66 and the other pair formed of an aperture 69 disposed opposite the outlet from the side extension. These apertures 25 constitute nozzles for directing the liquid onto their respective motors. Slidably and rotatably mounted in the sleeve 67 is a solid rod 70 forming a valve to control the nozzles 68 and 69 and having a plurality of 30 sets of parallel transversely positioned passageways 71, there being one set for each of the nozzles. Either the passageways of one set are disposed at an angle to the passageways of the other set or the apertures are angularly disposed so that when one of the 35 apertures is opened to one of its passageways, the solid portion of the rod closes all of the passageways of the other set. The passageways have different sized openings 40 or bores to control the character of the streams through the nozzles. The relative arrangement of the passageways in each set are preferably similar. In case it is desired 45 to change the speed of the motor when on either direct or reverse drive, the valve rod 70 is moved longitudinally in the sleeve 67 to bring the different sized passage-ways into communication with the nozzles.

The position of the valve rods 70 controlling each set of nozzles is determined by a single actuating rod 72, so mounted as to be either rocked or moved longitudinally. Said rod 72 is connected to the valve rods 70 by means of connecting links 73, which comprise yokes 74 which straddle the rod 72 and are connected thereto by pivot pins 75 and also comprising cams 76 engaging in longitudinal slots 77 provided in the rods 70.

In order to lock each of the rods 70 in set 65 position, a portion of the top of each sleeve

67 is preferably formed of a locking or guiding plate 78 having a central longitudinal slot 79 and a plurality of oppositely disposed slots 80, one for each of the passageways 71 in the rod and having the same relative arrangement as the passageways. Affixed to each valve rod 70 and extending therefrom through the slots is a locking pin 81. The nozzles are so positioned relative to each other and to the slots that with the pin 75 disposed in the central slot 79 both of the nozzles are closed by the solid rod, but when the rod is rocked to bring one of the passageways into communication with one of the nozzles, the pin is moved at the same time to 80 fit into one of the transverse or lateral slots 80.

The operation of the engine is as follows:—

With the parts in the position shown in Fig. 2, and with the cylinder to the right filled with liquid and with suitable excessive liquid in the well at the bottom of the casting the steam or other elastic fluid under pressure is admitted from a suitable supply 85 not shown, to this cylinder. The pressure of the steam will be uniformly distributed over the liquid by the baffle plate 23 without injury to the liquid and will force the liquid through the outlet 21, the conduits 65 and 90 the nozzle to drive the motor. As the liquid is forced out of the cylinder, the baffle plate is driven downward carrying with it the stem 26 and the lever 28, thus placing the powerful spring 29 under tension. When 100 the lever 28 has been carried downward into engagement with the collar 64, the exhaust valve 61 is positively opened relieving the pressure in the cylinder. Immediately the baffle plate begins its return stroke under 105 the force of the spring 29, thus tending to create a vacuum in the lower portion of the cylinder 17, which causes the liquid in the well to raise the valve 19 and flow through the inlet 18 to fill the portion of the cylinder below the baffle plate. The return movement of the baffle plate is regulated to the necessary extent by any suitable means as the spring check valve 64^a in the exhaust pipe. The exhaust valve remains open, 110 while the lever 28 rises being held in its open position by the spring 62 until it is positively closed.

As the baffle plate rises, the stem 26 engages the arm 43 on the rod 42 and carries 115 same upward, compressing the spring 45 and forcing the head 46 into engagement with the roller 48. The wedging action of the head swings the lever 50 on its pivot until the roller 48 engages the beveled 120 surface 53 on the stop 52, thus releasing the roller, whereupon the frame 35 that is operatively connected with the inlet valve 33 is snapped upward with a very 125 rapid movement, by either or both of the 130

springs 45 and 35^a. Just before the inlet valve is open, however, the lug 28^a of the lever 28 engages with the upper collar 64 on the stem of the outlet valve, thus positively closing said valve against the tension of the spring 62. The upward and outward movement of the roller 48 causes the roller 54 to swing into the path of the beveled surface 58 upon the plate or flange 57 connected 10 to the baffle plate. As the baffle plate is forced downward by the steam, the beveled surface engages with said roller 54 and forces the same outward, thus positively closing the inlet valve and causing the roller 48 to resume its initial position below the stop 52.

The same cycle of operation occurs in each of the cylinders 17, but the steps preferably occur in alternate order, so that a 20 practically continuous stream of liquid will be forced against the motor, the liquid being forced from one cylinder while the other cylinder is being filled.

The nozzle control for all of the cylinders 25 is actuated from the single control rod 72, which extends outside the casing. By moving the rod 72 longitudinally, each of valves 70 is rocked about its axis to bring a set of transverse passage-ways 71 into communication 30 with its corresponding nozzles 68 or 69, as the case may be, thus operating either the forward or reverse drive accordingly as desired. By rotating the rod 72, however, the valve 70 is moved longitudinally to 35 change the passageways 71 so as to vary the character of the stream passing through the nozzle. The arrangement of the passageways through the valve is such that only one passage-way can be opened at the same time either in the forward or reverse driving positions of the rod. The valve 70 is locked in position by causing the pin 81 to seat in one of the slots 80.

In my improved construction, the baffle 45 plate 23 separates the liquid from the steam or other expansive fluid so that a suitable degree of superheated steam may be utilized and any suitable liquid may be used without being disintegrated or destroyed. The 50 baffle plate not only acts to distribute uniformly the steam or other expansive fluid pressure over the entire head of the liquid piston, thus utilizing the full force of the expanding steam, but also provides means 55 for controlling the fluid inlet and outlet valves and for refilling the cylinder with the liquid. In effect, the level of the liquid in the cylinder determines the operation of the valves so that the timing of the valves 60 is automatically regulated. The engine is governed from a single operating arm or lever which not only determines the size of the stream employed, but also determines whether the forward driving motor or the 65 reverse driving motor shall be actuated and

permits the streams to be diverted gradually from one to the other, thus changing the direction of rotation of the driven shaft without shock or jar. It will be noted also that the passages through the control valve may 70 be positioned so that, streams may be directed against both the forward and the reverse driving motors, simultaneously, thus balancing the engine and bringing it to a standstill without stopping the liquid actuating mechanism. It is obvious also that many changes within the knowledge of those skilled in the art may be made in the particular mechanism herein shown and described, without departing from the invention, provided the means set forth in the 80 following claims be employed.

Having thus described my invention, I claim:

1. A fluid operated engine comprising a 85 closed housing providing a liquid reservoir in the bottom thereof, a liquid in said reservoir, a Pelton wheel mounted within said housing; means for forcing the liquid against said wheel to rotate the same in 90 either direction, said means including a cylinder having a valve controlled liquid inlet opening into said reservoir, means tending to create a reduction of pressure in said cylinder for drawing the liquid from said reservoir into said cylinder, and a steam supply directed to said cylinder for driving the liquid therefrom into operative engagement with said wheel, valvular means contained within said housing for controlling said 95 steam supply and manually controlled means extending exteriorly of the casing for controlling the direction of rotation of said Pelton wheel.

2. In a device of the class described, the 105 combination of a cylinder, a baffle plate reciprocating in said cylinder and separating the same into a liquid chamber and a steam chamber, a valve controlled inlet and a valve controlled outlet for said liquid chamber, a 110 stem extending from said baffle plate to the outside of said cylinder, steam inlet and exhaust for said steam chamber, valves controlling said inlet and exhaust, and mechanical connections between said stem and steam 115 controlling valves for timing the opening of said valves.

3. In a fluid operated engine, a liquid 120 drive including a cylinder, a baffle in said cylinder for dividing the same into a steam space and a liquid containing space, mechanical means exteriorly of the cylinder operatively connected to said baffle and acting thereon to return the same to its normal position and an exhaust valve mechanism having an element thereof disposed in the path of movement and adapted to be engaged by an element of said mechanical means thereby to actuate the valve mechanism.

4. In a device of the class described, the combination of a cylinder, a baffle plate reciprocating in said cylinder and separating the same into a liquid chamber and a steam chamber, a valve controlled inlet and a valve controlled outlet for said liquid chamber, a stem extending from said baffle plate to the outside of said cylinder, a steam inlet and a steam exhaust for said steam chamber, 5 valves controlling said inlet and exhaust, mechanical connections between said stem and steam controlling valves for timing the opening of said valves, and means acting on said stem tending to return the baffle plate 10 to its normal position when free of the steam pressure.
5. In a fluid operated engine, the combination with a motor and a liquid for driving the motor, of means for forcing the liquid 20 against the motor comprising a cylinder adapted to contain the liquid, a baffle movable in said cylinder, a valve for admitting fluid under pressure to said cylinder, valve operating mechanism, said mechanism 25 including a plate upon a stem fixed to the baffle and projecting exteriorly of the cylinder for opening and closing said inlet valve as the plate approaches the limits of its movements.
- 30 6. In a fluid operated engine, the combination with a motor and a liquid for driving said motor, of means for forcing said liquid against the motor comprising a cylinder having a valve controlled fluid inlet and outlet, a baffle plate fitting said cylinder, means controlled by said baffle plate for operating the outlet valve, means for automatically 35 opening the inlet valve in predetermined position of the baffle plate and means acting 40 on said valves tending to maintain them in set position.
7. In a fluid operated engine, the combination with a motor and a liquid for driving the motor, of means for forcing said liquid 45 against the motor comprising a cylinder provided with a valve controlled fluid inlet, a movable baffle plate in said cylinder, means for automatically opening said inlet, a trip mechanism normally holding said valve in 50 its closed position and means controlled by said baffle plate for actuating said trip mechanism to release the automatic valve opening mechanism.
8. In a fluid operated engine, a motor, a 55 liquid for driving the motor, means for controlling the liquid comprising a cylinder, a baffle plate reciprocating in said cylinder and forming a cover for the liquid, a liquid inlet and outlet to said cylinder at one side 60 of said baffle plate, an inlet for the actuating fluid on the opposite side of said baffle plate, and a spring lever controlled exterior of the cylinder acting on said baffle plate to return the same to its initial position and 65 permit the liquid to flow into said cylinder through said liquid inlet.
9. In a fluid operated engine, a motor, a liquid for driving the motor, means for controlling the liquid comprising a cylinder, a baffle plate reciprocating in said cylinder, 70 means for guiding said baffle plate in its reciprocatory movements, means for admitting an expansive fluid to said cylinder to move said baffle plate in one direction, and spring controlled means mounted exteriorly of the 75 cylinder and energized by the movement of said baffle plate, tending to return the baffle plate to its initial position.
10. In a liquid operated engine, the combination with a motor, of means for driving 80 the liquid onto said motor, said means including a cylinder, a baffle plate reciprocating therein, a steam inlet and exhaust to said cylinder, a valve controlling the exhaust and normally closing the same, a lever actuated 85 by said baffle plate, a valve stem connected to said valve, said lever being adapted to engage said stem to open said valve.
11. In a fluid operated engine, a motor, means for driving the liquid against the motor, said means including a cylinder, a baffle plate in said cylinder, said cylinder having an inlet and an outlet for the fluid on one side of the baffle plate, normally closed valves 90 for said inlet and outlet actuated by said baffle plate and independent of the liquid level in the cylinder and a liquid inlet on the other side of the baffle plate adapted to admit liquid into the cylinder, said baffle plate 95 preventing said fluid from commingling 100 with the liquid.
12. In a liquid driven motor, means for driving the liquid comprising a cylinder, a baffle plate mounted for reciprocatory movement in the cylinder, mechanical means exteriorly of the cylinder for moving the baffle plate in one direction to introduce the liquid into said cylinder, said baffle plate controlling the admission of steam to the cylinder to expel the liquid from the cylinder 110 and energize said mechanically actuated means and valves actuated independently of the liquid level in the cylinder for controlling the admission of steam to the cylinder. 115
13. In a liquid driven engine, a motor, a liquid piston for actuating said motor, and means for actuating said liquid piston, said means including a cylinder, a baffle in the cylinder forming a head to the end of the piston remote from the motor and provided 120 with an extension projecting exteriorly of the cylinder, a steam inlet port opening into the cylinder to one side of the axis thereof for directing steam on said head, means adapted to be engaged by said projecting 125 extension for regulating the admission of steam through said port, an exhaust valve and means to operate it.

14. In a liquid driven engine, a cylinder, a baffle plate therein dividing the cylinder into liquid and steam containing compartments, a spring positioned exteriorly of the cylinder actuating said baffle plate to draw liquid into the liquid compartment, and valvular means controlled by the position of the baffle plate and independent of the liquid for admitting steam into said steam compartment to act on the liquid through the baffle plate.

15. In a liquid actuated engine, a motor, a nozzle control for directing a liquid onto said motor, said nozzle control comprising a sleeve having a pair of transversely disposed openings therein, one of said openings constituting a nozzle for directing a stream on said motor, and the other of said openings adapted to form a communication with a liquid supply conduit, a valve rod mounted for rotary movement in said sleeve and having a plurality of passageways extending transversely therethrough and means for bringing one of said passageways into position to form a fluid communication between said openings and means for shifting the rod longitudinally to bring another of said passageways into position to form another fluid communication between said openings.

16. A valve control for fluid driven engines comprising a sleeve having two pairs of oppositely disposed openings therein, said pairs being angularly disposed relative to each other, a valve rod rotatably mounted in said tube having a plurality of sets of transversely extending passageways therethrough, one set for each of said pairs of openings, and means for rotating said valve rod to bring one of said transverse passageways into position to form a liquid communication between a pair of said openings and to close the other of said openings, means for shifting said rod into position to close both pairs of said openings, and means for locking said valve rod in position.

17. A valve control for fluid driven engines comprising a sleeve having a plurality of pairs of oppositely disposed openings therein, said pairs being angularly disposed relative to each other, a valve rod rotatably mounted in said sleeve having a plurality of sets of transversely extending passage-ways therethrough, one set, consisting of a plurality of different size passageways, for each of said pairs of openings, and means for rotating said valve rod to bring one of said transverse passage-ways into position to form a fluid communication between a pair of said openings and to close the other of said openings.

18. A nozzle control for fluid driven engines, comprising a sleeve having a pair of transversely disposed openings therein, a valve rod slidably and rotatably mounted in said sleeve, said rod having a plurality of

transversely extending passageways therethrough and means for sliding said rod longitudinally to bring said passage-ways into position to form a liquid communication between said openings, and for rotating said rod when in any position to close communication therethrough.

19. In a liquid driven engine, a pair of spaced supports, a motor comprising a Pelton wheel having its hub journaled in said supports, a shaft mounted in said supports independently of said wheel and extending through said hub, and means connecting said wheel with said shaft to drive the same.

20. In a fluid driven engine, a motor mounting comprising a pair of spaced supports, a plurality of Pelton wheels having a single hub journaled in said supports, a shaft journaled in said supports and a gearing connecting said shaft with said hub thereby to drive said shaft.

21. In a fluid driven engine, a motor comprising a plurality of Pelton wheels having hollow hubs coupled together to form a housing, a plurality of separated shaft sections in said housing, and a differential gearing between the adjacent ends of said shaft sections supported by the hubs of said wheels.

22. In a fluid driven engine, a cylinder, a steam inlet valve for said cylinder, mechanism for opening said valve, comprising a slidably mounted frame, a spring, a rod controlled by the spring, a stop interposed in the line of movement of said rod, a baffle plate within the cylinder, means attached to the baffle plate for moving said rod and compressing said spring, and means for moving said stop out of the path of said rod to permit the spring to move said frame and open the valve.

23. In a fluid operated engine, the combination of a valve, a means for operating said valve comprising a slidably mounted frame, provided with a pair of spaced sleeves, a spring controlled rod slidably mounted in said sleeves, said rod having a pin movable in the space between said sleeves, a stop adapted to intercept the movement of said rod and means adapted to move said rod into engagement with said stop to remove the same from its intercepting position and means acting on said frame to actuate the valve when said stop is moved.

24. In a fluid operated engine, the combination with a movable member subjected directly to the force of the fluid, a valve controlling the inlet for the fluid, a trip mechanism for actuating said valve comprising a spring energized by said fluid actuated member, and a trip locking means including a lever adapted to be moved to its unlocking position by said spring, and adapted to be moved to its locking position by the movement of said fluid actuated member.

25. In a fluid operated engine, a member driven in one direction by the fluid, spring controlled means driving said member in the opposite direction, a valve controlling the fluid inlet, valve actuating device including a shiftable mechanism, means independent of said spring controlled means normally maintaining said mechanism in locked position, and means for unlocking and actuating said mechanism adjacent the end of the movement of said member in one direction, said member having a free movement prior to its engagement with said mechanism.
- 10 26. In a fluid operated engine, a plate driven in one direction by the fluid, a spring for driving said plate in the opposite direction, a valve controlling the inlet of said fluid, mechanism automatically actuating said valve, means for locking said mechanism, means for moving said locking means into inoperative position when the plate is driven by the spring and means for moving said locking means into operative position when the plate is driven by the fluid.
- 15 27. In a fluid operated engine, a stationary post, a head plate and a stop carried by said head plate, a member driven by the fluid in one direction, automatic means for moving said member in the opposite direction, a valve controlling mechanism slidably mounted on said post, a means normally interposed between said mechanism and said stop for locking said mechanism from movement in one direction, and means carried by 20 said member for moving said locking means into inoperative position.
- 20 28. In a fluid operated engine, means for controlling the fluid comprising a post and a head plate, a frame slidably mounted on said post, said frame including a pair of spaced sleeves, a spring controlled rod slidably mounted in said sleeves, said rod having a beveled head, a lever fulcrumed to said frame, a roller carried by one arm 25 of said lever and normally disposed in the path of movement of said beveled head, a stop carried by the plate tending to resist the movement of said lever and frame in one direction, and means for forcing said head 30 into engagement with said roller to displace same relative to said stop, and means for automatically moving the frame on said post.
- 25 29. In a fluid operated engine, the combination with a movable member driven by
- the fluid, a valve controlling the fluid inlet, an actuating mechanism for the valve including a supporting post, a frame slidably mounted on said post and connected to the valve, so that the movement of the frame 60 actuates the valve, a rod slidably mounted in said frame, a spring disposed between said rod and frame, said rod designed to be engaged by said movable member to place the spring under tension and means 65 for delaying the release of said spring until the same is under tension, said spring when released designed to shift the frame and actuate the valve.
- 15 30. In a fluid operated engine, the combination with a movable member driven by the fluid, a valve controlling the fluid inlet, an actuating mechanism for the valve including a supporting post, a frame slidably mounted on said post and connected to the 70 valve, so that the movement of the frame actuates the valve, a rod slidably mounted in said frame, a spring disposed between said rod and frame, said rod designed to be engaged by said movable member to place 75 the spring under tension, means for delaying the release of said spring until the same is under tension, said spring when released designed to shift the frame and actuate the 80 valve and resilient means for cushioning the 85 movement of said frame.
- 20 31. In a fluid operated engine, the combination with a movable member driven by the fluid, a valve controlling the fluid inlet, an actuating mechanism for the valve including a supporting post, a frame slidably mounted on said post and connected to the 90 valve, so that the movement of the frame actuates the valve, a rod slidably mounted in said frame, a spring disposed between 95 said rod and frame, said rod designed to be engaged by said movable member to place the spring under tension, and a member disposed in the path of movement of said rod when acted upon by the spring 100 for delaying the movement of the rod until the spring has acquired a definite tension, said spring when released designed to shift the frame and actuate the valve.

This specification signed and witnessed 105
this 25th day of April, A. D. 1913.

ENOCH RECTOR.
